CLAIM

The ornamental design for a console for fluid recycling, as shown.

DESCRIPTION

FIG. 1 is a left side, front perspective view of a recycling console showing our new design;

FIG. 2 is a bottom plan view thereof;

FIG. 3 is a top plan view thereof;

FIG. 4 is a front elevational view thereof;

FIG. 5 is a right side elevational view thereof;

FIG. 6 is a left side elevational view thereof; and,

FIG. 7 is a rear elevational view thereof.

The broken line drawing of a pull-out instruction panel in FIGS. 1, 5-7 is for illustrative purposes only and forms no part of the claimed design.
